UNITED STATES PATENT OFFICE.

ELLIICK H. GOLLINGS, OF CHICAGO, ILLINOIS.

ROTARY POWER DEVICE.

1,378,855.

Specification of Letters Patent.

Patented May 24, 1921.

Application filed March 10, 1919. Serial No. 281,892.

To all whom it may concern:

Be it known that I, ELLICK H. GOLLINGS, a citizen of the United States, and a resident of the city of Chicago, county of Cook, and

5 State of Illinois, have invented certain new and useful Improvements in Rotary Power Devices; and I do hereby declare that the following is a full, clear, and exact description of the same, reference being had to the 10 accompanying drawings, and to the numerals of reference marked thereon, which form a part of this specification.

My invention has reference more particularly to a rotary power device comprising 15 eccentrically arranged members having fluid compartments therebetween, whereby fluid is passed through the device by rotation of either member.

It is an object of my invention to provide 20 an improved rotary power device which may be used either as a pump or motor.

Another object of my invention is to provide a rotary power device comprising eccentrically arranged inner and outer members 25 with a chamber therebetween having swinging partitions, operating upon rotation of either member to afford corresponding enlarging and diminishing compartments adapted to effect a transfer of fluid 30 through the device.

Another object of my invention is to provide a rotary power device comprising eccentrically arranged inner and outer members with a chamber therebetween having 35 swinging partitions, operating upon rotation of one of the members to afford corresponding enlarging and diminishing compartments to effect a transfer of fluid through the device, the said partitions being adapted to interlock with one another as the device is operated, to afford an effective separation between the enlarging and diminishing compartments.

A further object of my invention is to 45 provide a rotary power device comprising eccentrically arranged rotary members either of which may be held stationary as the other is rotated to thereby effect a transfer of fluid through the device, and in which 50 each member rotates only in one direction which is opposite to the direction of rotation of the other member, and such rotation of either member effects a transfer of fluid in the same manner through the device. In 55 other words, the device may be driven in

either direction to effect the same transfer of fluid, or in case it is used as a motor, by forcing fluid therethrough in one direction, a drive therefrom in either direction may be secured. .

My invention also has other important objects which will appear from the following specification and the accompanying drawings, in which I have described and illustrated my invention in a preferred form.

On the drawings:

Figure 1 is a side view of a device constructed in accordance with my invention.

Fig. 2 is an enlarged transverse sectional view on the line 2—2 of Fig. 1.

Fig. 3 is a sectional view on the line 3—3 of Fig. 2.

Fig. 4 is a view partly in section on the line 4—4 of Fig. 2, with the inner drum or rotor in elevation.

Fig. 5 is a sectional view on the line 5—5 of Fig. 2.

Fig. 6 is a fragmentary sectional view on the line 6—6 of Fig. 5.

Fig. 7 is an enlarged vertical sectional view of substantially one half of the device, said section being taken through the axis thereof.

Fig. 8 is a view, partly in section, on the line 8—8 of Fig. 1.

Fig. 9 is a similar view on the line 9—9 of Fig. 1.

Fig. 10 is a view, similar to Fig. 2, of a modified form of the device.

Fig. 11 is a fragmentary view similar to Fig. 10, showing a different stage of the operation.

As shown on the drawings:

Referring first to Figs. 1 to 9 inclusive, the reference numeral 1 indicates the base 95 of the device upon which are mounted pairs of bearing supports 2—3, 4—4, and 5—5. The bearing support 3 is cut away at 6 for a purpose hereinafter indicated and thus differs from its corresponding bearing support 2, but otherwise the bearing supports of each pair are alike and serve the same purpose. Each of these bearing supports is composed of a pair of half sections, as shown in Figs. 8 and 9, with opposite semi-circular half bearings, at their upper ends, which are clamped around the portion of the device engaged therein, by means of bolts 21 and 22, which connect the half sections above and below the bearings.

110

5 Mounted between the bearings 2 and 3, is a casing comprising a drum 7 which is closed at its ends by the plates 8 and 9, each of which is provided with an axial sleeve or hub extension 49, journaled in the respective bearings 2 and 3 to support the casing for rotation.

10 Mounted within the casing 7—8—9 is a hollow cylinder 10, the end walls 11 of which are spaced apart so as to fit closely against the end plates 8 and 9 of the casing and permit relative rotation thereof, and a tubular hub 12 is arranged eccentrically on each end wall 11 of the cylinder 15 10, and in alinement with one another, each of said hubs being journaled in the sleeve 49 of its adjacent end plate 8 or 9, as shown in Fig. 7.

20 Secured within each hub 12 or, if desired, made integral therewith, is a hollow shaft or pipe 13, which extends outwardly and is journaled in the bearing 4 and extends into the bearing 5. Each bearing 5 has mounted therein the enlarged end 14 of a pipe which 25 communicates with the hollow shaft 13, and has the end of the latter journaled therein as shown in Fig. 7, one of these pipes, which serves as the inlet when the device is used as a pump and as the outlet when used as a 30 motor being indicated at 15, and the other, which serves as the outlet when the device is used as a pump and as the inlet when used as a motor, being indicated at 16. Each of the enlarged ends 14 is held against rotation in its respective bearing 5 by set screws 35 17^a, which are threaded through the bearing and engage in the wall of the enlarged end 14.

40 The inner end of each enlarged pipe end 14, and the outer end of each hub 49, are similarly formed to provide a fluid tight joint with the respective pipes 13, and permit relative rotation, and to this end each 45 has a stuffing box with packing material 17 therein which is pressed into the stuffing box by a packing ring 18, the latter being clamped against the packing by bolts 19, secured to the end of the enlarged pipe end 14 or hub 49, and engaged through an 50 annular flange 20 of the packing ring.

55 The cylinder 10 is divided, intermediate of its ends, into separate compartments 23 and 24, by means of a diametrical partition 25, which is offset at the center as shown in Fig. 3, so that the diametrically opposite arcuate slots or openings 26 and 27 communicate respectively with the compartments 23 and 24, the ends of these slots being separated by the intervening wall portions 28 and 29.

60 A plurality of partitions 30 are pivotally mounted in the casing 7—8—9, at equal intervals, and adjacent the inner periphery of the drum 7, on shafts or bolts 31, which 65 extend between and through the end walls

8 and 9, so as to support the partitions and also secure the end plates to the drum, and these partitions are engaged by springs 32, so that the inner ends of the partitions bear constantly against the outer periphery of the cylinder 10. These partitions are of suitable width to engage closely against the end walls 8 and 9, of the casing without interfering with their pivoted movement, and the pivoted end of each partition is of cylindrical contour to fit and rock in correspondingly shaped transverse grooves 33, so that these partitions serve as valves to separate the annular space between the cylinder 10 and casing 7—8—9 into separate compartments and prevents appreciable leakage therebetween.

70 Obviously, as the cylinder 10 and casing 7—8—9 are eccentrically arranged, rotation of either one, while the other is held stationary, results in a successive swinging of the partitions 30, those occupying the space where the walls of the cylinder 10 and drum 7 are closest together being swung outwardly 75 as shown at the bottom of Fig. 2, and those occupying the space where the cylinder and drum are separated the greatest distance being swung inwardly by their springs 32, as shown at the top of Fig. 2, and inasmuch as the inner ends of the partitions bear constantly against the cylinder 10, those intermediate of these two positions are at successively increasing or decreasing angularity 90 to the inner face of the drum 7.

95 Of course, as the cylinder 10 or casing 100 7—8—9 revolve, the partitions 30 are constantly changing their positions, and the wall portions 28 and 29 between the slots 26 and 27 are sufficiently long so that one, at 105 least, of the partitions 30, is engaged therewith at all times, thus effectively separating one half of the annular space between the drum 7 and cylinder 10 (which half communicates through the slot 26 with the chamber 23) from the other half of the space between the drum and cylinder (which half communicates through the slot 27 with the chamber 24).

110 Each of the partitions 30, at its free end, is offset so as to have a shoe portion 34 with two angular faces 35 and 36, the former of which fits and engages the periphery of the cylinder 10 as it rides along the slot separating portion 29 of the cylinder wall and insures sufficient engaging surface to prevent leakage between the chambers at opposite sides of the partition, and the latter of which fits and engages, for the same purpose, the periphery of the cylinder 10, as it rides along the slot separating portion 28 of the cylinder wall, these being the two places of contact of the partitions 30 with the cylinder wall where leakage is to be obviated to as great an extent as possible.

115 As a further measure to avoid leakage as 120 125 130

the partitions ride along the portion 28 of the cylinder wall, each partition is provided with an angular or rib portion 37, on the outer face; which, as the end of the partition 5 slides over the cylinder portion 28, engages and is held against the cylindrical surface of the outer end of the preceding partition, as shown in Fig. 2. Such engagement, however, by reason of the cylindrical surface 10 with which the rib 37 contacts, does not interfere with the movement of the partition, engaged by the rib 37, which is required to maintain its free end engaged with the surface of the cylinder 10.

15 In order to apply power to this device for operating it as a pump or to transmit power therefrom, if used as a motor, the side wall 9 of the casing 7—8—9 has an annular flange 38, at the outer side, or a circular series of 20 lugs, if preferred, to which a gear ring 39 is secured, the bearing support 3 being cut away at 6 to accommodate this gear, and a gear wheel 40 is also keyed at 41 on the tubular shaft 13, so that each rotary element 25 of the device may receive or transmit power.

When one of the rotary elements is rotated, the other is usually maintained stationary, and for the purpose a number of set screws 42 are threaded through the bearings 30 4, and adapted, when the shaft 13 and cylinder 10 are to be held stationary, to be turned down into engagement with countersinks 43 (see Fig. 9) provided therefor in the shaft 13. These cap screws are withdrawn or removed, when the shaft 13 and cylinder 10 are to rotate.

Similar cap screws 44 are threaded into the bearings 2 and 3, so as to engage similar countersinks in the hubs 9 of the end plates 40 8 and 9 of the casing of the device when the latter is to be held stationary.

In Figs. 10 and 11, I have shown a modification of my invention which is the same as the previously described structure, except 45 as to the partitions 45, and the same reference numerals are used to designate the parts that are alike in both structures.

The partitions 45, in this modified structure have a long inner face 46, to ride on the 50 face of the cylinder 10, when passing the slot separating portion 28 of the cylinder wall, and this face 46 is formed on a radius of curvature equal to the distance of the axis of the hubs 12 from the most eccentric 55 point on the outer face of the cylinder 10, so that as such point comes into contact with the face 46, there is no further pivotal movement of the partition until this point moves out of contact with the face 46. The back 60 of the partition also has a rib or angular flange 47, which cooperates with the cylindrical pivoted end of the preceding partition in the same manner as the rib 37 of the previous construction and as the partition, 65 while riding over the slot separating portion

28, does not swing, the contact of the rib 47 with the cylindrical pivoted end of the partition 45 will be maintained during this time. Furthermore each succeeding partition rib 47 is brought into contact with the preceding partition previous to the disengagement of the rib of such preceding partition with its preceding partition, thus insuring a thorough separation between the intake and outlet compartments of the device. 70 This separation is also assured by the increased extent of engagement of the surface 46 with the wall of the cylinder 10 as it rides over the slot separating portion 28 thereof.

75 The operation is as follows:

Assuming that the device is to be used as a pump, this may be accomplished by rotating either the drum 7—8—9 or the cylinder 10 in the proper direction while the other remains stationary, or by rotating both in 80 opposite directions. Gearing may be connected with the gears 39 and 40 to rotate either and adapted, when one is rotated to hold the other from rotation. However, for the purpose of illustration, and to provide a 85 simple and effective means of controlling the independent rotation of each, I have shown the set screws 42 and 44, the former of which are adapted to lock the cylinder 10 from rotation and the latter of which similarly lock the casing 7—8—9.

90 If it is desired to pump by rotating the casing 7—8—9, the set screws 44 are withdrawn sufficiently to permit rotation thereof, and the set screws 42 are turned down so as to seat in the countersinks 43 on the shaft or tube 13, and thereby hold the cylinder 10 attached thereto in a stationary position.

100 Power is then applied to the gear ring 39, to rotate the casing 7—8—9 in the direction indicated by the arrow A in Fig. 2, and the pipe 15 is connected with the source of fluid supply and the pipe 16 connected to convey the discharge from the pump to the point desired.

105 The rotation of the casing 7—8—9 carries the partitions 30 around the cylinder 10, the ends thereof being maintained in contact with the surface of the cylinder by the tension of the springs and also, at the points of greatest and least distance between the cylinder 10 and drum 7, which is the top and bottom respectively of Fig. 2. The tension of the springs is supplemented by the suction and pressure in the pump.

110 The arcuate space between the casing 7—8—9 and cylinder 10 is therefore divided by the partitions 30 into a plurality of compartments, certain ones of which communicate with one another through the slots 26 and 27 and their respective chambers 23 and 24, and it will be observed that by reason of the intervening wall portions 28 and 29, a partition is at all times engaged with the wall of the cylinder 10 at the point of great- 115 120 125 130

est separation between the drum 7 and cylinder and another partition at the point of least separation of the drum from the cylinder so as to prevent communication between the compartments, between the partitions 30, which are in communication with the slot 26 and chamber 23, and the compartments in communication with the slot 27 and chamber 24. The chambers in communication with the slot 26 are gradually enlarged as the drum 7-8-9 rotates in the direction indicated by the arrow A and fluid is drawn in through the pipe 15, hollow shaft 13, cylinder chamber 23 and slot 26 to fill these constantly enlarging compartments, and provide what is hereinafter termed the suction side of the pump, and as each compartment reaches its greatest capacity, the preceding partition is riding over the wall portion 29 of the cylinder 10 and the following partition moves over the wall portion 29 so as to interrupt communication with the slot 26 and isolate this compartment from the following compartments at the suction side of the pump.

The compartments between the partitions 30 which are in communication with the slot 27, are constantly decreasing in capacity as the casing 7-8-9 rotates in the direction A and afford what is hereinafter termed the pressure or discharge side of the pump, and as each compartment, which passes over the cylinder wall portion 29 and has been isolated from the suction side of the pump, comes into communication with the slot 27, it is gradually decreased in size so that the fluid therein is forced out through the slot 27, cylinder chamber 24, hollow shaft 13 and pipe 16. The continuing rotation of the drum 7-8-9, and the resilient continuous enlargement of compartments at the suction side of the pump and transfer of fluid therefrom to the discharge side of the pump, and the continuous diminution in size of the compartments at the discharge side of the pump effects a continuous passage of fluid through the pump.

When the pumping is to be affected by rotating the cylinder, the set screws 44 are turned down to hold the casing 7-8-9 stationary and the set screws 42 are withdrawn sufficiently to permit rotation of the cylinder 10. Power is then applied to the gear 40 to rotate the cylinder 10 in the direction indicated by the arrow B in Fig. 2, which direction, it will be noted, is reverse to that in which the casing is rotated for pumping. The effect upon the partitions is the same as in the previous operation of the pump, and results in a continuous diminution of the compartments between the partitions 30, in communication with the slot 27, and cylinder chamber 24, and a constant enlargement of the compartments in communication with the slot 26 and chamber 23, and a constant

suction of fluid in through the pipe 15, hollow shaft 13, cylinder chamber 23 and slot 26, and transfer of fluid from the suction side to the discharge side of the pump, and exhaust of the fluid through the slot 27, cylinder chamber 24, pipe 13 and pipe 16, as in the previously described operation.

Obviously the operation of the cylinder and casing may be combined, by applying power to both the gears 39 and 40, so as to rotate the casing and cylinder simultaneously in the opposite directions A and B respectively. This, however, would probably not be necessary, except perhaps in unusual cases, as the same result would be accomplished by increasing the rate of speed of either the cylinder or casing while the other was held stationary.

The operation of the device as a motor, it is thought will be readily understood without detailed description, as it is merely the reverse of the operation of the pump. When so used, fluid under pressure is introduced through what was the discharge side of the pump, viz. through the pipe 16, hollow shaft 13, cylinder chamber 24 and slot 27, and this fluid acts to enlarge the compartments, between the partitions 30, which are in communication with the slot 27, and to effect such enlargement causes the cylinder 10, or casing 7-8-9, or both to rotate. By adjusting the set screws 42 and 44, rotation of either the cylinder or casing or both is permitted, and power is furnished from the device by connections made with the gears 39 and 40.

The operation of the modified form of device shown in Figs. 10 and 11 is substantially the same as that described for the structure of Figs. 1 to 9 inclusive, except as to the time and point of contact of the partition 45 with the cylinder wall and with one another, which was clearly pointed out in the description of this particular structure, and further description of its operation is believed to be unnecessary.

While I have shown and described my invention in a preferred form, I am aware that various changes and modifications may be made therein without departing from the principles of my invention, and I therefore do not purpose limiting the patent granted hereon otherwise than necessitated by the prior art.

I claim as my invention:

1. In a device of the class described, the combination of a relatively rotatable casing and member, the latter being arranged eccentrically in the casing to afford an eccentric space therebetween and a plurality of partitions pivotally mounted on the casing and having the free ends thereof held under a resilient tension against the outer face of said member, the member having inlet and outlet ports extending peripherally there-

around, each port being longer than the distance between the free ends of adjacent pairs of partitions.

2. A device of the class described, the combination of a relatively rotatable casing and member, the latter being arranged eccentrically in the casing to afford an eccentric space therebetween, and a plurality of partitions pivotally mounted on the casing and having the free ends thereof held under resilient tension against the outer face of said member, the member having inlet and outlet ports therein, the partitions being adapted to contact with each other in their retracted position to prevent the passage of fluid therebetween.

3. A device of the class described comprising a relatively rotatable casing and member, the latter being arranged eccentrically in the casing to afford an eccentric space therebetween and a plurality of partitions pivotally mounted on the casing and having the free ends thereof held under a resilient tension against the outer face of said member, each of said ends having two adjacent contacting surfaces adapted to bear alternately against the member.

4. A device of the class described comprising a relatively rotatable casing and member, the latter being arranged eccentrically in the casing to afford an eccentric space therebetween and a plurality of partitions pivotally mounted on the casing and having the free ends thereof held under a resilient tension against the outer face of said member, each of said ends having two contacting surfaces adapted to bear alternately against the member, and a third surface adapted to bear against the partition adjacent thereto.

5. In a device of the class described the combination of a relatively rotatable casing and member, the latter being mounted eccentrically in the casing to provide an eccentric space therebetween, and having an inlet and an outlet to said space, a plurality of pivoted partitions dividing said eccentric space into separate compartments, some of which, upon relative rotation of the casing and member are gradually enlarged and communicate with said inlet and others of which are gradually diminished and communicate with the outlet, said partitions being adapted to interlock with one another and with the said member to separate the compartments in communication with the inlet from the compartments in communication with the outlet.

6. In a device of the class described the combination of a relatively rotatable casing and member, either of which may be fixed, the latter being arranged eccentrically in the casing to afford an eccentric space therebetween, a plurality of partitions mounted on the casing and having the free ends thereof held under resilient tension against the outer face of said member, said member having inlet and outlet ports therein, the partitions being adapted to contact with each other in their retracted position to prevent the passage of fluid therebetween.

7. In a device of the class described, the combination of a rotatable casing and a rotatable member, the latter being arranged eccentrically in the casing to afford an eccentric space therebetween; and a plurality of partitions pivotally mounted on the casing and having the free ends thereof held under a resilient tension against the outer face of said member, the member having inlet and outlet ports extending peripherally therearound, each port being longer than the distance between the free ends of adjacent pairs of partitions.

8. In a rotary power member the combination of a relatively rotatable casing and member, the member being arranged eccentrically in the casing, and having an inlet pipe and an outlet pipe extending therefrom and positioned concentrically of the casing, a hub on the casing at each side thereof and circling the pipe leading from the eccentric member, the casing being mounted on the hub and provided with a plurality of partitions pivotally mounted therein and having the free ends thereof held under resilient tension against the outer face of said member, means for stationarily supporting the eccentric member and inlet and outlet pipes, and means adjacent the casing for rotatably supporting the casing independently of the eccentric member and pipes.

In testimony whereof I have hereunto subscribed my name in the presence of two subscribing witnesses.

ELLIK H. GOLLINGS.
